UNITED STATES PATENT OFFICE.

ALBERT PRIESTMAN, OF PHILADELPHIA, PENNSYLVANIA.

FLUID-CONTROLLING APPARATUS.

Application filed October 23, 1922. Serial No. 596,525.

This invention relates to systems for automatically controlling the application and release of fluid under pressure and one object of said invention is to provide a relatively simple and substantial combination of apparatus involving the use of a number of controlling or regulating bleeds for determining the length of time during which pressure will be exerted.

10 I further desire to provide a novel system for governing the intermittent delivery and utilization of air under pressure, which shall require a reduced volume of air as compared with similar prior systems and at the same 15 time be highly efficient in utilizing such air.

Another object of my invention is to provide a simple, reliable system of apparatus for alternately supplying air under pressure to and exhausting it from a container, a 20 machine or other device for storing or utilizing it.

I also desire to provide a system having the above characteristics, especially designed for automatically controlling the times during 25 which air under pressure is admitted to or exhausted from any device capable of receiving or utilizing the same.

These objects and other advantageous ends I attain as hereinafter set forth, reference being had to the accompanying drawings, in which.

Fig. 1 is a diagrammatic elevation partly in vertical section, illustrating a system of apparatus for carrying out my invention;

30 Figs. 2 and 3 respectively are vertical sections illustrating the detail construction of portions of the apparatus shown in Fig. 1; and

Fig. 4 is a vertical section, to some extent diagrammatic, illustrating a modified form of my invention.

In Figs. 1 to 3 inclusive, 1 represents a tank or other source of air under pressure and 2 a device to which it is desired air shall be intermittently supplied and thereafter exhausted. For the sake of illustration this is shown as a tank having a pipe 3 through which a liquid such as sewage will be admitted and this pipe includes a 40 check valve 4. Also connected to the tank 2 is a discharge pipe 5 through which liquid is to be forced by air under pressure.

For governing the delivery of air to and its exhaust from the tank 2, I provide a 45 pipe 6 leading from the air supply tank 1 through a valve 7 to a cross fitting 8. From

the latter a pipe 9 leads to the device or tank 2 and through a second branch 10 said fitting is also connected to an exhaust valve 11 opening to the atmosphere. Through a fourth branch 12 the fitting 8 is connected to a casing 13 having a diaphragm 14 therein which through a rod or other suitable connection 15, governs the movable element 16 of the valve 7, the rising of this diaphragm when air under pressure is admitted below it causing opening of the said valve member.

The exhaust valve 11 includes a valve element 17 preferably so positioned as to tend to open under the action of gravity and acted on by a rod 18 extending into a casing 19 having a diaphragm 20. Fixed to the rod is a collar or equivalent structure 21 acted on by a spring 22 tending to move said rod into a position permitting opening of the valve member 17. A third diaphragm casing 23 is also provided and has associated with it a pilot valve 24 including an element 25 designed to be moved to its open position by a rod 26 actuated by the diaphragm 27 in said casing. This rod has a collar 28 acted on by a spring 29 tending to move it into a position such as will allow seating of the valve element 25 through a 80 pipe 30.

The valve 24 is connected with the air supply pipe 6, and on the other side of the valve element 25 a second pipe 31 connects said valve with the lower part of the diaphragm casing 13 as well as with the lower part of the diaphragm casing 19, the arrangement being such that air under pressure admitted to this pipe 31 will cause upward movement of the diaphragms of the casings 13 and 19 and corresponding upward movement of the rods 15 and 18.

The casing 23 below the diaphragm 27 is connected through a pipe 32 to a suitable source of fluid under pressure, such for example as a bell shaped structure 34 submerged within a liquid-containing tank 33. The bell being open at the bottom, permits liquid in or supplied to the tank 33 to compress air into the pipe 32, thus tending to raise the diaphragm 27 and through the rod 26 unseat the valve 25. The casing 23 above the diaphragm 27 is connected through a pipe 35 with the air pipe 9 leading to the tank 2 and includes a check valve 35^a designed to prevent flow of air from the diaphragm casing 23 while permitting flow to

said casing from the pipe 9. The pipe 35 has also connected to it an adjustable escape valve or bleed 36 designed to permit escape of air from said pipe and from the casing 5 23 above the diaphragm, at a predetermined definite rate.

That portion of the casing 19 below the diaphragm is connected through a pipe 37 with the pipe 31 and includes a check valve 10 38 for preventing flow of air from said casing back to the pipe 31 and, between this valve and said casing, has also connected an adjustable bleeder 39. The pipe 31 likewise has connected with it a third bleed- 15 er 40.

With the above described arrangement of parts the valve 16 is closed and if it be assumed that the tank 33 is filled with liquid or has liquid delivered to it, the resulting 20 air under pressure in the pipe 32 moves the diaphragm 27 upwardly in the casing 23 and unseats the valve member 25, allowing air under pressure to pass from the pipe 6 through the pipe 30 into pipes 31 and 37 25 and into the casing 19 below its diaphragm 20. As a consequence said diaphragm moves upwardly against the action of the spring 22 and closes the exhaust valve element 17 of the valve 11. At the same time air will 30 also pass from the pipe 31 into the casing 13 below the diaphragm 14 and likewise raise this, causing upward movement of the rod 15 and opening of the movable element 16 of the valve 7.

35 Air under pressure is now free to pass from the supply tank or other source 1 through the pipe 6 and valve 7 into the pipe 9 and tank 2, causing any liquid which may have been delivered to the latter to be discharged through the pipe 5. The delivery 40 of air under pressure to the pipe 9 results in flow of air through the pipe 35 to the casing 23 above the diaphragm 27, and the pressure of this air is sufficient to result in 45 the downward movement of said diaphragm, with the result that the rod 26 is moved down and the valve element 25 of the valve 24 is permitted to close.

There is now a definite amount of air 50 under pressure in the pipe 31 and the bleeder 40 is so adjusted that this air will leak out at a definite rate and in a definite time will permit the diaphragm 14 in the casing 13 to return to its normal position. The resulting downward movement of the rod 15 will now permit closure of the element 16 of the valve 7, thus cutting off the flow of air to the tank 2. The bleeder 39 is so set 55 as to likewise permit escape of air from the lower part of the casing 19 at such a rate that after the closure of the valve 7, the spring 22 will act to move the rod 18 and diaphragm 20 downwardly far enough to permit opening of the exhaust valve element 17. 60 The air under pressure in the tank 2 is now

permitted to exhaust to the atmosphere so that liquid may again flow into it from the pipe 3 through the check valve 4.

When the pressure of the air in the pipe 35 and upper part of the diaphragm casing 70 23 has fallen to a sufficiently low point, the compressed air in the bell 34 and pipe 32 will again cause upward movement of the diaphragm 27 and unseating of the valve 25 with a repetition of the above described cycle 75 of operations.

In that form of my invention shown in Fig. 4, I provide an air chamber 41 or other suitable container arranged to be supplied with air under pressure at definite intervals 80 by any suitable means. This container through a pipe 41^a is connected to one end of a cylinder 42 having an annular seat 43 designed to cooperate with the suitably formed adjacent end of a piston 44 normally 85 pressed toward said end by a spring 45 mounted on the rod 46 connected to said piston. The latter is provided with a longitudinally extending annular port 47 opening on its cylindrical face and through a 90 passage 48 connecting with the head of said piston adjacent the valve seat 43. In the walls of the cylinder are placed two ports 49 and 50 in such positions as to be successively placed in communication with the port 95 47 in the piston as the latter is moved longitudinally and in the present case upwardly, in the cylinder, and the rate of flow through these ports 49 and 50 may be regulated at will by means of needle valves respectively 100 indicated at 51 and 52.

The cylinder 42 has mounted on or connected to its upper end a casing 53 having a port 54 opening to the atmosphere, a second port 55 connected to the device or container 105 to be intermittently supplied with air under pressure and a third port 56 connected to a source of supply of air under pressure. Between the ports 54 and 55 is a passage 57 designed to be closed by a valve 58 carried on the upper end of the piston rod 46 and into this passage extends the stem 59 of the valve 60 mounted to control the flow of air from the port 56 to the port 55. This stem 110 is of such a length that it will be engaged by the valve 58 and the valve 60 will be unseated when said valve 58 moves into said passage. The valve 60 is normally pressed toward its seat by a spring 61 and when unseated by the stem 46 may be moved into such position as to close a port 62 connected with the air chamber 41 for the purpose of supplying air thereto.

Under conditions of operation, when air 120 under pressure is admitted to the pipe 41^a, it acts upon a limited portion of the lower face of the piston 44 within the valve seat 43. When said pressure has increased sufficiently to overcome the force of the spring 45, the piston 44 is moved upward to a slight 125 130

extent, thus permitting the air from the pipe 41^a to act on the whole of the lower face of said piston. As a result this latter moves upwardly in the cylinder 42, bringing the 5 air port 47 into communication with the bleed port 49 and the continued upward movement of the piston thereafter brings the port 47 into communication with the port 50. At the same time, the valve 58 on the piston 10 rod enters and closes the passage 57, thus cutting off the port 55 from the atmosphere and immediately thereafter striking the stem 59 and unseating the valve 60.

Air is now free to flow from the supply 15 port 56 through the port 55 to the device to be actuated and if it be assumed that the supply of air under pressure is cut off from the chamber 41 and pipe 41^a, as by the closing of the port 62, it will be understood 20 that by reason of the escape of the air in said pipe and chamber through the ports 47 and 50, the piston 44 will gradually move down in its cylinder 42 under the action of the spring 45. The rate of this movement will 25 depend upon the adjustment of the needle valve 52 and when it has progressed sufficiently far, the valve 60 will seat and cut off the flow of air to the port 55.

In the mean time air will continue to leak 30 through the port 49 so that under the action of the spring 45 the piston 44 will move toward the lower end of the cylinder 42 and ultimately withdraw the valve 58 from the passage 57. Thereupon the port 55 will be 35 placed in communication with the port 54, allowing the air still under pressure in the device connected to said port 55 to be exhausted. The continued escape of air through the port 49 will thereafter permit 40 the piston 44 to engage the seat 43, whereupon the system will remain quiescent until air under pressure is again delivered to the chamber 41 and pipe 41^a.

From the above description it will be appreciated that in both forms of my invention 45 it is possible to accurately control or regulate the time during which air under pressure is permitted to flow to a tank, machine or other apparatus capable of utilizing it. By 50 separate and independent means it is likewise possible to accurately determine and regulate the time which shall elapse after the air supply is cut off before the machine, etc. is permitted to exhaust the air under pressure which it still contains. In both 55 cases the apparatus required is relatively simple as well as rugged in construction and

is capable of close regulation to obtain the desired results.

I claim:

1. The combination in means for providing intermittent delivery of air under pressure, of automatic mechanism comprising two devices respectively adapted to open and close the air supply and to open and close the exhaust, and means including two independent bleeds for respectively regulating the operations of the said devices. 60

2. The combination in means for providing intermittent delivery of air under pressure, of automatic mechanism comprising two devices respectively adapted to open and close the air supply and to open and close the exhaust, and means including two adjustable independent bleeds for respectively regulating the operations of the said devices. 70

3. The combination in means for providing intermittent delivery of air under pressure, of inlet and exhaust valves; and controlling means for governing said valves including independent bleeds set to cause said valves to act successively. 80

4. The combination in means for providing intermittent delivery of air under pressure, of inlet and exhaust valves; motor devices for actuating said valves; and independent bleeds set to predetermine the times of operation of said devices. 85

5. The combination in means for providing intermittent delivery of air under pressure, of inlet and exhaust valves; air operated motor devices for actuating said valves respectively; and independent bleeds for governing the times of operation of said devices. 90

6. The combination in means for providing intermittent delivery of air under pressure, of inlet and exhaust valves; air operated motor devices for actuating said valves 100 respectively; independent bleeds for governing the times of operation of said devices; with a pilot valve controlling said devices.

7. The combination in means for providing intermittent delivery of air under pressure of inlet and exhaust valves; air operated motor devices for actuating said valves respectively; independent bleeds for governing the times of operation of said devices; a pilot valve controlling said devices; and a bleed controlling the operation of said pilot valve. 105

ALBERT PRIESTMAN.
